DESIGN FOR A BROOCH MOUNTED WATCH-CASE OR SIMILAR ARTICLE

Emanuel Deutsch, New York, N. Y.

Application March 15, 1946, Serial No. 127,564

Term of patent 14 years

(Cl. D42—8)

To all whom it may concern:

Be it known that I, Emanuel Deutsch, a citizen of the United States of America, residing in New York city, county of New York, and State of New York, have invented a new, original, and ornamental Design for a Brooch Mounted Watch-case or Similar Article, of which the following is a specification, reference being had to the accompanying drawing, forming part thereof, wherein, mounted watch case or similar article showing my new design.

I claim:

The ornamental design for a brooch mounted watchcase or similar article, substantially as shown.

EMANUEL DEUTSCH.
